UNITED STATES PATENT OFFICE.

SAMUEL M. RIKER, OF CHESTER, NEW JERSEY.

BELT-BUCKLE.

1,380,416.

Specification of Letters Patent. Patented June 7, 1921.

Application filed May 29, 1920, Serial No. 385,182. Renewed March 31, 1921. Serial No. 457,425.

To all whom it may concern:

Be it known that I, SAMUEL M. RIKER, a citizen of the United States, residing at Chester, in the county of Morris and State 5 of New Jersey, have invented certain new and useful Improvements in Belt-Buckles; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 The present invention has reference, generally, to improvements in buckles; and, the present invention relates, more particularly, to improvements in belt buckles of the pivoted clamp-jaw type, the said pivoted clamp-jaw means being of such novel construction that it readily adjusts itself to any thickness of belt body arranged operatively therewith, and to this end my invention provides a 20 novel construction of clamp-jaw arranged in 25 novel relation to the pivoted loop-member from which the same springs.

The invention, therefore, has for its principal object to provide a simply constructed and easily manipulated belt buckle of the 30 general construction hereinafter described; and, the invention has for a further object to provide a novel construction of pivoted clamp-jaw member comprising a clamp-jaw carried by a pivoted loop-member, said 35 clamp-jaw being more or less yieldable whereby the same will readily accommodate itself in operation to various thicknesses of belt bodies with which the buckle may be employed without unduly straining or 40 stressing the buckle parts while nevertheless providing an adequate gripping or clamping effect when in use.

Other objects of the present invention, not at this time more particularly enumerated, 45 will be clearly understood from the following detailed description of the same.

With the various objects of the present invention in view, the same consists, primarily, in the novel belt buckle hereinafter 50 set forth; and, the invention consists, furthermore, in the novel arrangements and combinations of the various devices and parts, as well as in the details of the construction of the said parts, all of which will 55 be more fully described in the following

specification, and then finally embodied in the appended claims.

The invention is clearly illustrated in the accompanying drawings, in which:

Figure 1 is a front face view of my novel 60 construction of belt buckle operatively associated with a belt body. Fig. 2 is a rear face view of the same. Fig. 3 is a side edge elevation of the same. Fig. 4 is a longitudinal section through the same, taken on line 4—4 65 in said Fig. 1, and drawn on an enlarged scale; and Fig. 5 is a transverse section of the same, taken on line 5—5 in said Fig. 4.

Similar characters of reference are employed in all of the above described views, 70 to indicate corresponding parts.

Referring now to said drawings, the belt buckle shown therein comprises a main member or buckle body consisting of a face plate 1, which is preferably outwardly convexed, and which is provided along its longitudinal edges with rearwardly projecting side flanges 2. Said side flanges are provided, adjacent to one end of the buckle body, with outwardly pressed portions 3 80 providing, on the inner faces of said side flanges, transversely opposed depressed bearing seats 4.

The reference-character 5 indicates the transverse base portion of a pivoted loop 85 member from which extends outwardly beyond the adjacent end of the buckle body a loop portion 6. Said base portion 5 is provided at its opposite ends with outwardly projecting journal lugs 7, which are sprung, 90 respectively, into the depressed bearing seats 4, thereby pivotally connecting said loop member between said side flanges 2, and spaced rearwardly from the back or inner side of said face plate 1. Integrally connected with outer edge of said base portion 5, intermediate the outwardly projecting side portions 6' of the loop portion 6, is a clamp 95 jaw which comprises an upwardly and rearwardly curved jaw body 8 projecting toward 100 the back or inner side of said face plate 1, said jaw body 8 terminating in a free gripping or biting edge 9 spaced freely above the inner face of said base portion 5, intermediate the latter and the back or inner side 105 of said face plate 1.

Said side flanges 2 are preferably provided, adjacent to the opposite end of the buckle body, with another pair of outwardly pressed portions 10 providing, on the inner 110

faces of said side flanges, transversely opposed depressed bearing seats. A pintle member 11 is provided with its respective ends engaged in said bearing seats, so that the same is mounted to extend transversely between said side flanges 2 and spaced rearwardly from the back or inner side of said face plate 1. Rotatably arranged on said pintle member 11 is a roller member 12.

10 In attaching a belt body 13 to the buckle, one end 14 is looped and fastened about the free end of said loop portion 6 so as to have a fixed relation thereto. In applying the belt and buckle to the waist of the wearer, the belt body 13 is carried around the waist, and the free end 15 of the belt body is inserted between the back of the face plate 1 and roller member 12, and then passed between the back of the face plate 1 and the clamp jaw body 8 (the loop member being swung inwardly toward the body of the wearer to rotate said base portion 5 thus swinging away from the back of the face plate 1 the said jaw body so that the belt end may be easily moved longitudinally between said parts), and then drawn up to tighten the belt body around the waist to the desired degree. When the belt body is thus adjusted about the waist, the tension to which the same has been adjusted tends to pull upon the loop-member 6, swinging the latter in a direction toward the face plate 1, thereby forcing the biting edge 9 of the clamp jaw 8 against the belt, whereby the latter is firmly gripped between said clamp jaw 8 and said face-plate, and the free end of the belt held unyieldingly against withdrawal from such engaged relation to the buckle.

Owing to the peculiar shape, position and arrangement of the clamp jaw 8 relative to the loop member 6 and the supporting base portion 5, the said biting edge 9 of the clamp jaw is rendered more or less yieldable, so that the same will yield when forced against

belt bodies of more than ordinary thickness 45 without loss of clamping effect, and so that in all cases the loop member 6 will readily move to normal outwardly projected relation to the end of the buckle body.

I claim:—

1. A belt buckle comprising a face plate, longitudinal side flanges projecting rearwardly from said face plate, a pivoted clamp device comprising a base portion having journal lugs journaled in the walls of said side flanges adjacent to one end of said face plate and spaced rearwardly from the back of the latter, a loop member projecting outwardly from the outer edge of said base portion, and a jaw body integrally formed with 60 said base portion to spring from the outer edge of the latter intermediate the side arms of said loop member, said jaw body being curved upwardly and rearwardly to provide a free biting edge spaced intermediate the 65 back of said face plate and the inner face of said base portion.

2. A belt buckle comprising a body member, a clamp device pivoted to said body member, said clamp device comprising a 70 base portion, a loop member projecting outwardly from the outer edge of said base portion, and a jaw body integrally formed with said base portion to spring from the outer edge of the latter intermediate the side 75 arms of said loop member, said jaw body being curved upwardly and rearwardly to provide a free biting edge spaced intermediate the back of said body member and the inner face of said base portion.

In testimony that I claim the invention set forth above I have hereunto set my hand this 28th day of May, 1920.

SAMUEL M. RIKER.
